UNITED STATES PATENT OFFICE.

JAMES S. DAYTON, OF CUMBERLAND, MARYLAND.

BUGGY AND RACK FOR HANDLING TIN.

1,333,472.

Specification of Letters Patent.

Patented Mar. 9, 1920.

Application filed March 14, 1919. Serial No. 282,741.

To all whom it may concern:

Be it known that I, JAMES S. DAYTON, a citizen of the United States, residing at Cumberland, in the county of Allegany and State of Maryland, have invented new and useful Improvements in Buggies and Racks for Handling Tin, of which the following is a specification.

The object of my invention is to provide a buggy and rack for the expeditious and economical handling of sheets of tin in a tin mill or analogous plant; the said buggy and its complementary rack being designed more particularly for use in conjunction with the apparatus for handling tin sheets constituting the subject matter of my contemporary application, filed January 18, 1919, Serial Number 271,867, as hereinafter explicitly set forth.

20 The novelty, utility and practical advantages of the buggy and rack will be fully understood from the following description and claims when read in connection with the accompanying drawings, hereby made a part hereof, particularly when it is stated that the rack is adapted to be transported on the buggy and to be lifted from and replaced on the buggy.

In the drawings:

30 Figure 1 is a side elevation showing the rack properly positioned on the buggy.

Fig. 2 is an end elevation of the same.

Fig. 3 is a plan view of the buggy body *per se*.

35 Fig. 4 is a horizontal section taken in the plane indicated by the line 4-4 of Fig. 1, looking downwardly.

Fig. 5 is an enlarged detail showing the mounting of one of the upstanding pins.

40 Similar numerals of reference designate corresponding parts in all of the views of the drawings.

My novel buggy, generally designated by 1, is preferably motor-driven, and is designed to be moved on tracks 2 by power derived from an overhead trolley wire 3 connected with a suitable source of electrical energy. The body 4 of the buggy is preferably in the form of a hollow casing mounted on wheels 5, and in the top wall 6 of said body and adjacent to the ends thereof are slots 7 which extend throughout the width of the wall 6. At their transverse centers the said slots 7 are in communication with comparatively short longitudinally-disposed openings 8 which extend in opposite direc-

tions from each of the slots 7, as shown. It will also be noticed by reference to Fig. 3 that the top wall of the buggy body is provided with apertures 4a which are scattered throughout its area and are designed to permit water to pass downwardly when the rack is removed from the pickler or water vat and is superimposed on the body 4. At this point I would have it understood that at its under side the body 4 is open so as to permit the water to drain to the ground.

The rack 9 of my improvement is preferably formed entirely of copper or brass so as to resist the action of the acids generally employed in tin mills. Among other elements the said rack 9 comprises transverse lowermost portions 10 shaped in conformity to the slots 7 and offsets 8 in the top of the body 4 and adapted to seat in said slots 7 and offsets 8 with a view to precluding both endwise and sidewise displacement of the rack. Superimposed upon and fixed with respect to the said lowermost portions 10 are longitudinally disposed spaced bars 11. Between these bars 11 are other bars 12 tapered upwardly in cross-section, as shown, and said bars 12 are provided at intervals in their length with sockets 13 to receive the reduced lower ends 14 of upstanding pins 85 15 that are preferably tapered to points at their upper ends as illustrated, and designed to separate the tin sheets, indicated by 16 into bunches. Rising from the outermost longitudinal bars 11 are uprights 17 which form the corners of the lifting frame of the rack. The said uprights 17 are connected or fixed adjacent to their upper ends to end bars 18 and side bars 19; and it will also be observed that the said corner uprights 17 are connected through trusses 20 with a loop or eye 21 designed for the attachment of a lifting and lowering apparatus, not shown. At 22 and adjacent to the ends of the innermost longitudinal bars 11 and arranged in vertically disposed sockets 13 in said bars, are upright rods. These upright rods 22 and the corner uprights 17 of the lifting and lowering frame are provided with enlargements 23, and on the said enlargements 23 are longitudinal rails 24 and 25 which rails are apertured to receive the corner uprights 17 and the rods 22, respectively, and are designed to hold the two longitudinal series of tin sheets against endwise displacement while permitting a certain amount of endwise play of said tin

sheets as is desirable in the handling and treatment thereof. The end portions of the longitudinal bars 11 are preferably beveled, as indicated by 26 for the engagement of the 5 dogs on the groups of tangs in the apparatus of my beforementioned contemporary application; the said groups of tangs being designed to be inserted endwise between the longitudinal bars 11 to lift the bundles of 10 tin sheets 16 clear of the pins 15 and then withdraw the said bundles from the rack in the direction of the length thereof.

In the practical use of my novel buggy and rack, the rack is charged with tin sheets at 15 that point in a mill where the tin is "opened." The buggy with the rack thereon is then moved to the scale for the weighing of the tin. The buggy with the rack thereon is then moved on a storage track, and when 20 a vat is opened for use, the rack is lifted from the buggy and put in the vat for the purpose of pickling the tin. At the proper time the rack is moved from the pickler to the water vat, and from the water vat the 25 rack is removed and is then replaced on the buggy. At this time the apparatus constituting the subject of my before-mentioned contemporary application is put into use to remove the bunches of tin from the rack, and 30 then the operation described, so far as the buggy and rack are concerned, is repeated.

It will be apparent from the foregoing that my novel buggy and rack are adapted to materially facilitate the handling of 35 sheets of tin in tin mills and analogous plants so as to contribute to economy in operation.

It will further be apparent from the foregoing that my novel rack is constructed 40 with a view to expeditiously and thoroughly draining the water that is shed by the tin sheets as they come from the water vat, and in this the rack is assisted by the foraminations in the top wall 6 of the buggy body 4.

Having described my invention, what I 45 claim and desire to secure by Letters-Patent is:

1. A wheeled body having a foraminous top wall and transverse slots in said top wall 50 and also having offsets extending longitudinally from said slots, and a rack comprising lowermost transverse portions with offsets adapted to seat in the slots and offsets of the body, longitudinal spaced bars 55 arranged above and fixed with respect to said lowermost portions and having verti-

cally disposed sockets, upstanding pins removably arranged in said sockets and carried by said longitudinal bars, a lifting and lowering frame having corner uprights, upright rods socketed in the innermost longitudinal bars; the said upright rods and corner uprights having supports at an intermediate point in their height, outer retaining rails mounted on the corner uprights and superimposed on the supports thereof, and inner retaining rails mounted on the said upright rods and superimposed on the supports thereof.

2. A wheeled body having a foraminous top wall and transverse slots in said top wall and also having offsets extending longitudinally from said slots, and a rack comprising lowermost transverse portions with offsets adapted to seat in the slots and offsets of the body, longitudinal spaced bars arranged above and fixed with respect to said lowermost portions and having vertically disposed sockets, upstanding pins removably arranged in said sockets and carried by said longitudinal bars, a lifting and lowering frame having corner uprights, upright rods socketed in the innermost longitudinal bars; the said upright rods and corner uprights having supports at an intermediate point in their height, outer retaining rails mounted on the corner uprights and superimposed on the supports thereof, and inner retaining rails mounted on the said upright rods and superimposed on the supports thereof; some of the longitudinal bars of the rack being tapered upwardly in cross-section, and the upstanding pins being tapered to points at their upper ends.

3. A buggy having a wheeled body, and a lifting and lowering rack removably arranged on the buggy body and having longitudinal portions and means on said portions for retaining tin against horizontal displacement; the said longitudinal portions being spaced apart.

4. A buggy having a wheeled body, and a lifting and lowering rack removably arranged on the buggy body and having longitudinal portions and means on said portions for retaining tin against horizontal displacement; the said longitudinal portions being spaced apart, and the ends of the said longitudinal spaced portions being beveled.

In testimony whereof I affix my signature.

JAMES S. DAYTON.
